UNITED STATES PATENT OFFICE.

DAVID P. CLARK, OF DAYTON, OHIO.

LOCOMOTIVE TOY.

SPECIFICATION forming part of Letters Patent No. 768,268, dated August 23, 1904.

Application filed September 22, 1902. Serial No. 124,312. (No model.)

To all whom it may concern:

Be it known that I, DAVID P. CLARK, a citizen of the United States, residing at Dayton, in the county of Montgomery and State of Ohio, have invented certain new and useful Improvements in Locomotive Toys, of which the following is a specification, reference being had therein to the accompanying drawings.

10 This invention relates to locomotive toys, and has for its object to produce a toy of this description in which the motive power is stored in and derived from an inertia-wheel which is positively connected with one or 15 more of the running-wheels by spur-gearing.

To this end the invention consists in certain novel features, which I will now proceed to describe, and will then particularly point out in the claim.

20 In the accompanying drawings, Figure 1 is a side elevation of a construction embodying my invention. Fig. 2 is a plan view of the same.

In carrying out my invention I employ in 25 conjunction with a suitable frame an inertia-wheel of considerable weight and running-wheels supporting the frame and inertia-wheel, one or more of said running-wheels being positively connected by spur-gearing with 30 the inertia-wheel, so that in imparting its initial movement to the inertia-wheel by moving the running-wheels along and in contact with a suitable surface a high speed will be positively imparted to the inertia-wheel, the 35 motion of which will subsequently be positively transmitted to the running wheel or wheels when the toy is placed upon a suitable surface and released.

In the form of construction shown, 1 indicates the frame, and 2 the inertia-wheel, provided with an axle 3, mounted in fixed bearings 9 in the frame. The frame is supported on running-wheels 5, having axles 6 mounted in the frame. The inertia-wheel shaft is provided with a pinion 7, which meshes with a gear 8, secured on one of the axles 6, and the wheels 5, or at least one of them connected with this axle must be secured thereon, so as to rotate therewith.

50 By reason of the construction which I have

devised the toy may be prepared for operation by moving it over a suitable surface with the running-wheels pressed against said surface, whereby a rapid movement of rotation will be positively imparted to the inertia-wheel. The toy may then be operated by placing it upon a suitable surface and releasing it, whereupon the inertia-wheel will positively impart its rotary movement to one or more of the running-wheels, and thus cause 60 the toy to travel a considerable distance.

The structure is less expensive in cost of production than that class of locomotive toys wherein the running-wheels are frictionally driven by contact of the inertia-wheel axle 65 with their peripheries, since it is not necessary to accurately turn or finish the rims of the running-wheels, as in the case of such frictional toys.

It will be understood, of course, that a suitable toy-body of any kind may be secured to or mounted on the frame; but the particular character of this toy-body forms no part of my present invention, and I have therefore not illustrated it.

70 It will be noted that the axis of the inertia-wheel is horizontal and parallel with the axis of the driven wheel or wheels and in approximately the same horizontal plane therewith, so that the structure is compact and the center of gravity is low. This permits the attachment of any desired toy-body to the frame and insures the structure against top-heaviness, so that it will not tumble over in use.

75 I do not wish to be understood as limiting myself to the precise details of construction hereinbefore described and shown in the accompanying drawings, as it is obvious that these details may be modified without departing from the principle of my invention.

I am aware that locomotive toys have heretofore been constructed wherein a frictional contact between the inertia-wheel axle and the rims of the running-wheels has been utilized for the purpose of transmitting power 95 between the running-wheels and the inertia-wheel. In such a construction, however, there is possible a slipping of the friction-surfaces upon each other which will result in a loss of power in transmission, which loss of power 100

is manifestly impossible where spur-gearing is employed, as in my present improvement. Furthermore, this frictional transmission requires a special finishing of the rims of the running-wheels, which is not necessary in my preferred form of construction, and also involves a variable relation between the bearings of the running-wheels and of the inertia-wheel axle, which in my preferred construction I am enabled to do away with.

Having thus fully described my invention, what I claim as new, and desire to secure by Letters Patent, is—

A locomotive toy, comprising a frame, running-wheels mounted therein, a large spur-gear positively connected with one of the running-wheels, an inertia-wheel having a hori-

zontal axle parallel with the axis of the driven running-wheel and mounted in fixed bearings in the frame in approximately the same horizontal plane therewith, whereby the center of gravity of the toy is made low, said axle having a spur-pinion thereon which meshes directly with the spur-gear, the relations between the running-wheel axis and the inertia-wheel axis being fixed, substantially as described.

In testimony whereof I affix my signature in presence of two witnesses.

DAVID P. CLARK.
